EXPANDING PLUG OR MANDREL

Jerry Jay Dunn, Ellwood City, Pa., assignor to
 National Tube Company, a corporation of New
 Jersey

Application June 19, 1930, Serial No. 462,292

2 Claims. (Cl. 78—103)

This invention relates to mandrels for use in the manufacture of seamless metal tubes and has in view the provision of a device of this class by means of which the quality or the resultant product is improved and the life of the mandrel prolonged.

Generally speaking, the improvement consists in dividing the mandrel into a plurality of sections or parts which when assembled, form a unit having a smooth, unbroken, gradually expanding surface contour, the sections being free to rotate relatively to one another about the common axis of the mandrel, thus permitting each section to rotate at the speed of rotation of the interior surface of the material or partly-formed tube in contact therewith, thereby reducing frictional wear on the mandrel and surface and internal strains and stresses on the tube undergoing the cross-rolling process.

20 Heretofore mandrels comprising independently rotatable parts, each part being substantially similar to a one-piece mandrel, have been proposed. In such structures, each part has been given a conical or conoidal shape and cooperates with a similarly shaped surface portion of the rolls, the tube being first fed over the piercing point, which is in effect a one-piece mandrel in itself, then converging around a necked portion of the mandrel and then expanding over the next part. It has been found, however, that such constructions are impractical and do not function as contemplated, the same frictional wear being present in such instances as in a one-piece mandrel as commonly used.

35 The advantages of the improved mandrel will become apparent in view of the following description taken in conjunction with the drawing, wherein:

Figure 1 is a view in section and elevation 40 of a mandrel constructed in accordance with the features of the invention, together with a set of rolls and a billet or partly formed tube undergoing the cross-rolling operation.

Figures 2 and 3 are views in section taken on 45 the lines II—II and III—III, respectively, of Figure 1.

The reference numeral 5 designates a pair of rolls, which rotate on axes which do not intersect. The axes are so located with reference to 50 each other that by giving the proper shape to the rolls a pass is formed therebetween which first converges in the direction of travel of the billet or partly formed tube, indicated at T, and then diverges. The axes of the rolls and pass 55 are so located that the rotation of the rolls tends

to impart to the tube or billet a rotary motion and a motion of translation along its axis of rotation.

The improved mandrel or expanding point is particularly adapted for tubes of a size requiring more than one piercing operation. The mandrel or head is supported against endwise movement by a bar 6, said bar being provided with an enlarged annular portion 6^a formed with a bearing surface and a conical shaped boss or 65 cylindrical projection 7, the latter serving to center the mandrel or head and maintain it in axial alinement with the supporting bar 6. The mandrel or head assembly is shown partly in section and comprises a point end 8 formed with a cylindrical projection or boss 9 which fits into a part 10 and maintains the end 8 in alinement with the mandrel as a whole, the parts 8 and 10 70 being free to rotate independently of each other.

The part 10 is that portion of the mandrel or 75 head which performs the major portion of the piercing operation and consequently bears the brunt of the endwise thrust imposed on the mandrel. The better to resist this thrust, the part 10 is provided with a recessed cylindrical projection 12 which is directly attached to the supporting bar 6, the recess in the said projection receiving the boss 7 formed on the end of the bar. By this means, the endwise thrust imposed on the part 10 is communicated directly to the 85 supporting bar 6, the part 10 rotating at the same angular velocity as the said bar.

The parts of the mandrel or head assembly 90 which are shown in section and indicated at 13 and 13^a function to smooth the inside of the tube and guide the latter as it becomes less and less elliptical in cross-sectional contour. These parts may if desired be formed in one piece and are bored to fit over the cylindrical portion 12 and rotate freely thereon. The part 13^a bears against 95 the bearing surface of the enlargement 6^a of the supporting bar 6.

In operation, the heated billet is pushed into 100 contact with the surfaces of the rolls 5, which are rotated and advance the rotating billet in an axial direction, bringing it into contact with the point 8 of the mandrel assembly.

The point 8 then starts to rotate in unison with the material, which continues to advance and flows over the point, coming into contact 105 with the part 10, the latter in turn then starting to rotate in unison with the rotating billet. The angular velocity or speed of rotation of the part 10, however, is of a different ratio than the angular velocity of the point 8, due to the increase 110

in cross-sectional diameter of the then oval tube T, note Fig. 2.

As the billet or partly-formed tube continues to advance, it reaches the parts 13 and 13^a, which likewise start to rotate in unison with the interior surface of the tube in contact therewith. As the rolling operation continues, the respective parts of the mandrel assembly each rotate at the same angular velocity as the interior surface of the partly-formed tube coming in contact therewith.

The advantages of a mandrel constructed as herein described over a one-piece mandrel and also over a mandrel which is comprised of a plurality of one-piece mandrels, as it were, will be obvious. When the advancing billet reaches the mandrel, the wall thickness is reduced by a rolling action. A portion of the reduction takes place in an axial direction but the major portion is in a circumferential direction and causes an increase in diameter. Further advance brings the billet into the diverging part of the pass, and thereafter the ovality of the partly-formed tube is gradually reduced, until as the tube passes out of contact with the rolls, it is circular in cross-section. It is apparent that the rolls tend to impart different angular velocities to different sections of the material in the pass. This tendency is resisted by the cohesion of the particles of the material to the extent that, roughly speaking, all sections rotate at the same angular velocity.

It is also apparent that at any cross-sectional point, the mandrel tends to rotate at the same surface speed as that of the inside surface of the tube at that point. The perimeter of the inside surface of the tube section is greater than that of the corresponding section of the mandrel, the ratio between these two quantities varying, being much less at some sections than at others. As the tube rotates at a constant velocity, it follows from this variable ratio that the tube tends to cause the mandrel to rotate at different angular velocities at different sections.

If, therefore, the mandrel is formed in one piece, it can have at any one time only one rate of angular speed, and hence the tube at each respective section except one will slide over the surface of the material, retarding flow of the material being worked and causing wear on the

mandrel. This action also exerts stresses on the material during formation of the tube which have a detrimental effect on the quality of the resultant product.

By making the mandrel of several parts or sections which are free to rotate relatively to each other, the friction generated between the interior surface of the partly-formed tube and the surface of the mandrel in contact therewith is reduced to a minimum, with the result that the quality of the tube is improved by the avoidance of needless stresses in its formation and the life of the mandrel is prolonged, which in turn affects the quality of the tube, as the best form of mandrel is maintained in service over longer periods of operation.

The herein described type of mandrel may also be used for expanding and smoothing with the same advantageous results. It will also be obvious that suitable bearings or bearing material may be used between the various rotating parts and that various modifications in structure may be adopted without departing from the scope of the invention.

What is claimed as new is:

1. A mandrel of the class specified, comprising, in combination, a rotatable supporting bar provided with a cylindrical projection, a frusto-conical piercing extremity formed in sections having relative rotation, one of which is formed with a recessed cylindrical projection adapted to receive the projection on the supporting bar, and an annular independently rotatable body section mounted on and encircling the cylindrical projection of the said piercing extremity section.

2. A mandrel of the class specified, comprising a rotatable supporting bar formed with a cylindrical projection and a bearing surface, a frusto-conical section formed with a recessed cylindrical projection which receives the projection on the supporting bar and bears against said bearing surface, an annular body section mounted to rotate on and encircling said recessed projection and also bearing against said bearing surface, and an independently rotatable end section also formed with a cylindrical projection which fits into a recess formed in said frusto-conical section.
